US0D1004415S

(12) **United States Design Patent** (10) **Patent No.:** **US D1,004,415 S**
(45) **Date of Patent:** **** Nov. 14, 2023**

(54) **HOOK**

(71) Applicant: **John Garcia**, River Edge, NJ (US)

(72) Inventor: **John Garcia**, River Edge, NJ (US)

(**) Term: **15 Years**

(21) Appl. No.: **29/820,051**

(22) Filed: **Dec. 20, 2021**

(51) LOC (14) Cl. **07-06**

(52) U.S. Cl.

USPC **D7/683**; D7/688

(58) **Field of Classification Search**

USPC D7/683, 688; D8/14, 367, 400; D22/149
CPC A47J 43/283; A47J 37/0786; A47J 43/18

See application file for complete search history.
